UNITED STATES PATENT OFFICE.

DAVID W. KETCHUM, OF EVANSTON, ILLINOIS.

PACKAGE FOR BLEACHING AND PACKING ROSIN.

SPECIFICATION forming part of Letters Patent No. 487,091, dated November 29, 1892.

Application filed May 7, 1892. Serial No. 432,147. (No model.)

To all whom it may concern:

Be it known that I, DAVID W. KETCHUM, a citizen of the United States, residing at Evans-
5 ton, in the county of Cook and State of Illino-
is, have invented a new and useful Improve-
ment in Packages for Bleaching and Packing
Rosin, of which the following is a specifica-
tion.

In the trade rosin is graded by its color, the
10 rosin being considered the better the paler it
is, and accordingly commanding the higher
price in the market.

The object of my improvement is to provide
15 a form of receptacle in which to harden and
uniformly bleach the rosin, which shall adapt
receptacles containing the finished product to
be secured together face to face in pairs, forming
20 with each pair a shipping-package of the
rosin peculiarly convenient for handling and
transportation and for access to the contents.

To apply my improvements, I proceed, generally stated, as follows: I run the rosin hot
from the still into open receptacles, the essential
25 features of each of which are that it shall
have a flat bottom, at least on the interior,
and be lined on its bottom, at least, with whitish
material and so shallow that the light,
30 an important bleaching agent, can penetrate
through it from top to bottom and that vapor-
ization or cooling can take place readily and
rapidly from the bottom upward. Free and
prolonged exposure to the elements, which
35 my shallow flat-bottomed receptacle conveniently
permits, is all that is necessary to produce
the desired bleaching effect, the sunlight,
air-currents, and the elements generally, in-
cluding rain and other forms of moisture, all
40 seemingly contributing to the desired end.
I find, however, that the best results are pro-
duced by providing for quite profuse vola-
tilization from the surface of the rosin.

My improvement is illustrated in the accom-
panying drawings, in which—

Figure 1 is a view in perspective of a shal-
45 low male tray filled with rosin; Fig. 2, a simi-
lar view of a like female tray; Fig. 3, a simi-
lar view of a package of the finished rosin,
composed of the two filled trays secured to-
50 gether face to face ready for shipment and
convenient for handling; and Fig. 4, a section
taken at the line 4 on Fig. 3.

A is the male tray, which I form, prefer-
ably, of rough wood, and the joints in the
base of which may, to prevent leakage, be
tongued and grooved. The preferred dimen-
55 sions of the tray are about forty-five inches
long, thirty inches wide, and five inches deep.
The stated dimensions, however, are merely
suggestive, as they may be varied within pro-
portions that will not defeat my purpose with-
60 out thereby departing from my invention.

B is the female tray, in all respects like the
tray A, except that it is provided about the
edge of its open side or face with a strap or
strip, cleat or flange r, adapted to overlap and
65 fit the edge about the face of the tray A and
be adapted to have nails or screws driven
through it into the sides of the male tray to
hold the latter and the female tray together,
and thereby form the package C, represented
70 in Fig. 3, the ledge about which, afforded by
the surrounding strip r, provides a convenient
gripping place for handling the package.

The rosin, hot from the still, (and in which
is left a quantity of spirits of turpentine suf-
75 ficient to insure more or less profuse vola-
tilization—say from two to five per cent. of
the entire quantity,) is poured into the shal-
low trays A and B. These trays thus filled
are left for a considerable period—say from
80 thirty to sixty days, more or less—in the open
air exposed to the elements—sunlight, air, and
rain—which gradually bleach it, and I find
that the bleaching effect is enhanced by pro-
viding each tray with a white lining or base
85 q, which may be whitewash, or which I pro-
vide in the form of white paper fastened on
the bottom of the tray and the provision of
which renders the less important the tongue
and groove construction of the joints in the
90 base of the tray.

The peculiar advantage in leaving a con-
siderable quantity of spirits of turpentine in
the rosin appears to be due to the more pro-
fuse decolorizing effect it produces by carry-
95 ing off the coloring material vaporized by the
heat of distillation with the volatilization of
the turpentine.

The depth of each tray should not exceed
that at which the sunlight can penetrate, and
100 vaporization can take place readily from the
bottom of the rosin contents, though the

length and width may be of any reasonable proportions. The dimensions I have stated, however, are preferred because they afford a capacity in the tray equal to about one-half 5 a barrel of rosin D, so that the full double-tray package C may contain about an ordinary barrel of rosin.

The flat-bottomed-tray form of receptacles, so desirable for bleaching the rosin, is peculiarly advantageous for a package C, inasmuch as it is neat, very convenient for handling and shipping, and cheap, not requiring expensive wood nor skilled labor to produce it, and it saves cooperage and hoop-irons, with 15 the great trouble commonly experienced in maintaining the latter tight, owing to their tendency to slip and loosen on the barrel.

The package of rosin C, in addition to the advantages stated as being incidental to it, 20 may be readily opened by separating the trays to expose the contents to inspection.

What I claim as new, and desire to secure by Letters Patent, is—

1. The shallow flat-bottomed bleaching-tray

provided with a white lining and filled with 25 rosin, substantially as described.

2. The shallow flat-bottomed bleaching-tray provided with a lining of whitewash and filled with rosin, substantially as described.

3. A package of rosin comprising, in combination, a pair of open-faced shallow trays provided with a lining of whitewash and filled with rosin and secured together face to face, substantially as described.

4. A package of rosin comprising, in combination, a pair of open-faced flat-bottomed shallow trays A and B, provided with a lining of whitewash and containing rosin D, the tray B having a marginal flange *r* about the edge of its open face, and the two trays being 40 adjusted together face to face with the tray A, enveloped about its edge by and fastened to the tray B through the flange, substantially as described.

DAVID W. KETCHUM.

In presence of—

JOHN HOGE,

J. W. WIPER.
